[57] CLAIM

The ornamental design for the 2-step ladder, as shown.

DESCRIPTION

FIG. 1 is a front right perspective of the 2-step ladder, incorporating the new design.

FIG. 2 is a rear view of the 2-step ladder of FIG. 1.

FIG. 3 is a side view of the right side of the 2-step ladder of FIG. 1; and,

FIG. 4 is a bottom view of the 2-step ladder of FIG. 1.

The left side of the 2-step ladder is the same as the right side shown in FIGS. 1 and 2.
